US00D763360S

(12) United States Design Patent
Rouse, Jr.

(10) Patent No.: US D763,360 S
(45) Date of Patent: * Aug. 9, 2016

(54) GAME BOARD

(71) Applicant: Raymond Earl Rouse, Jr., Laurel, MD (US)

(72) Inventor: Raymond Earl Rouse, Jr., Laurel, MD (US)

() Term: 15 Years

(21) Appl. No.: 29/534,854

(22) Filed: Jul. 31, 2015

(51) LOC (10) Cl. 21-01

(52) U.S. Cl.

USPC D21/338; D21/349

(57) CLAIM

The ornamental design for a game board, as shown and described.

DESCRIPTION

FIG. 1 is a front perspective view of a game board; FIG. 2 is a front elevation view thereof, the rear elevation view, the left side elevation view, and the right side elevation view being mirror images thereof; FIG. 3 is a top plan view thereof; FIG. 4 is a bottom plan view thereof; and, FIG. 5 is a front perspective view thereof, shown in use. The broken lines shown in the drawings illustrate portions of the game board that form no part of the claimed design.

1 Claim, 5 Drawing Sheets
